UNITED STATES PATENT OFFICE.

EARL B. ALDOUS, OF NORTH CREEK, NEW YORK, ASSIGNOR OF ONE-HALF TO WILLIAM H. FREEBURN, OF NORTH RIVER, NEW YORK.

INTERNAL-COMBUSTION ENGINE.

Application filed October 2, 1924. Serial No. 741,270.

This invention relates to an improved internal combustion engine and seeks, among other objects, to provide an engine which will be simple in construction and embody 5 but comparatively few parts but which will, nevertheless, be capable of developing high power.

The invention further seeks to provide an engine incorporating but a single rotary 10 valve to control both the intake and exhaust of each cylinder and wherein wear upon the valves will be automatically taken up as such wear occurs.

A further object of the invention is to 15 provide an engine embodying a novel form of piston and wherein means will be provided for effectually lubricating the wrist connection of the piston as well as the bearing 20 of the connecting rod at the crank pin.

The invention seeks, as a further object, to provide an engine wherein friction will be reduced to a minimum and wherein all moving parts subjected to hard wear will be 25 constantly lubricated.

And the invention seeks, as a still further object to provide an engine which will be silent and smooth in operation.

Other and incidental objects will appear hereinafter and in the drawings, wherein 30 I have illustrated the preferred embodiment of the invention,

Figure 1 is a vertical sectional view through one of the cylinders of my improved engine, the view being taken on the line 1—1 of Fig. 2 and looking in the direction indicated by the arrows;

Fig. 2 is a fragmentary sectional view at a right angle to Fig. 1;

Fig. 3 is a bottom plan view of one of the 40 valves;

Fig. 4 is a transverse section on the line 4—4 of Fig. 1, and looking in the direction indicated by the arrows, the valve being removed;

Fig. 5 is a transverse section on the line 5—5 of Fig. 1, looking in the direction indicated by the arrows and particularly showing one of the pistons;

Fig. 6 is a transverse sectional view taken at the level of Fig. 5, but looking upwardly, and

Fig. 7 is a fragmentary plan view showing one of the roller bearings employed.

Referring now more particularly to the

drawings, I employ a crank case 10 through 55 which is journaled a crank shaft 11. Roller bearings 12 are provided for the crank shaft, said roller bearings being of the character shown in detail in Fig. 7. Each of said bearings preferably comprises a plurality of rollers 13 connected by links 14 at the ends of the rollers to form a chain which may be readily assembled around the crank shaft. The rollers are provided with beveled end faces 15 and formed on the crank 60 shaft to coact with said faces are annular shoulders 16. Accommodating each of said bearings is a split sleeve or bushing 17 which is likewise formed near its ends with beveled annular shoulders 18 to coact with 65 the beveled faces of the rollers so that, as will be seen, the rollers will not only sustain the radial load of the crank shaft but will also coact between the shoulders of the 70 bearing sleeves and the shoulders of the 75 crank shaft to sustain any endwise thrust of the shaft, the rollers being so confined that the links at the ends thereof are relieved of any strain.

Formed in the crank case are openings 19 80 and resting on the crank case is a cylinder block embodying a plurality of cylinders 20 smaller in diameter than said openings. The engine may, of course, include any appropriate number of cylinders and mating with 85 said block is a head 21 closing all of said cylinders at their upper ends. Preferably a gasket, as shown, is employed between the head and block to provide a sealed joint therebetween and prevent the leakage of 90 water from the jackets of the head and block. Secured at their lower ends into the crank case at opposite sides of the cylinder block are rods 22 freely accommodated at their upper end portions through sleeves 23 95 on the head 21 and screwed upon the upper ends of said rods are nuts 24 tightly binding the head upon the block as well as binding the block upon the crank case. At the lower ends of the cylinders 20, the block is 100 provided at opposite sides thereof with flanges 25 to rest upon the crank case, and as shown in Fig. 1, the rods 22 are disposed to abut these flanges as well as the sides of the block for limiting the block against 105 transverse movement as well as movement longitudinally of the crank case. A secure and rigid construction is thus provided

while, at the same time, the cylinder block may be readily removed while the head 21 may be readily detached from the block.

Formed on the head 21 at its upper side 5 is a longitudinally extending gear case 26 normally closed by a cover 27 and, as shown in Fig. 2, the cover is provided with a filling plug 28. At the upper end of each of the cylinders 20, the head is formed with a hemi-spherical valve seat 29 from which rises an axial bearing 30 opening into the gear case 26 and fitting in said bearing is a bushing 31 provided at its upper end with a flange 32 seating against the bottom wall of the gear case. Rotatably fitting in the valve seats 29 are hemi-spherical valves 33 having axial stems 34 journaled through the bushings 31 and splined upon the upper end portions of the stems within the gear case 26 10 are like meshing valve gears 35 resting upon the flanges 32 of the bushings. Removably fitting over the upper ends of the stems are spring seats 36 secured by split retaining rings 37 fitting in grooves 38 in the stems 15 and bearing between the gears 35 and said seats are springs 39 pressing the valves 32 upwardly against their seats. Thus, as will be seen, wear upon the valves will be automatically taken up as such wear occurs. 20 However, to prevent undue frictional drag upon the valves I provide a means for relieving the upward thrust of the springs and sustaining a portion of such thrust. At their upper ends, the valve stem 34 are 25 provided with reduced spindles 40 and screwed through the gear case cover 27 are bearing plugs 41 recessed axially to journal said spindles. The plugs will thus co-operate with the bushings 31 to rotatably 30 support the valve stems and disposed in the recesses of the plugs are ball bearings 42 coacting between the plugs and the upper ends of the spindles to sustain the up-thrust of the springs 39. As will be perceived, the 35 plugs 41 may be adjusted for relieving the frictional drag of the valves against the valve seats as much as desired and screwed upon said plugs are nuts 43 locking the plugs in adjusted position. 40 At the forward ends of the cylinder block as well as the head 21 are aligned tubes 44 and journaled through said tubes and through a bracket 45 within the crank case 10 is a vertical shaft 45 upon the upper end of which is fixed a pinion 46 meshing with the forward one of the gears 35. Fixed to the lower end of said shaft is a beveled gear 47 and meshing with said gear is a beveled gear 48 fixed upon the crank 45 shaft 11. Thus, as will be at once understood, the valves 33 will be rotated by the crank shaft and the gearing is such that said valves are turned at a ratio of four to one with respect to said shaft. At one 50 side of the head 21 are spark plug openings 55 in which are removably mounted spark plugs 49 and formed in the lower edges of the valves at diametric points are, as shown in Fig. 3, semi-circular notches 50 to successively register with said openings for permitting ignition of the fuel charge in the respective cylinders. Opening through each of the valve seats 29 at the opposite side of the head are, as shown in Fig. 4, intake and exhaust passages 51 and 52 and formed in each of the valves to register with the inner ends of said passages are intake and exhaust ports 53 and 54. Thus, as will be appreciated in view of the foregoing, the intake and exhaust of the several cylinders 55 will be properly controlled by the valves as the valves revolve.

Removably fitting in the cylinders 20 from the lower ends thereof are sleeves 55 provided at their lower ends with radial annular flanges 56 snugly accommodated in the openings 19 of the crank case 10 and extending through said flanges are cap bolts 57 screwed into the flanges 25 of the cylinder block. The sleeves 55 may be of any approved metal to best withstand the wear of the engine pistons and, as will be observed, should any one of said sleeves become scored or otherwise impaired, it may be readily removed and renewed. Furthermore, by employing the sleeve, the cylinder block may, if desired, be of aluminum so that the weight of the engine may be maintained at a minimum. The flanges 56 of the sleeves will, of course, cooperate with the walls of the openings 19 for centering the cylinders above the crank shaft and locking the cylinder block in centered position and, as brought out in Fig. 1, the upper ends of the sleeves extend across the joint 105 between the head 21 and the block some distance thereabove to touch the lower edges of the valves 33 mating therewith. The sleeves thus serve to seal the joint between the head and the block so as to prevent the escape of compression and will also sustain the valves in active position should the valve springs 39 break. Further, the sleeves and the valves cover the entire inner surfaces of the cylinders and valve seats to 110 protect said surfaces from the injurious effects of ignition.

Slidable in the sleeves 55 of the cylinders 20 are hollow pistons 58, each of which is provided with an elongated skirt 59 of reduced thickness to define an internal annular ledge at the upper end of said skirt and opening through the wall of the piston at said ledge is, as shown in Figs. 5 and 6, a plurality of radial slots 60 defining intervening lugs 61. Formed in the sleeves 55 near their lower ends are circumferentially spaced openings 62 located to register with the outer ends of the slots 60 when the pistons each reach the lower end of their stroke 120 125 130

and formed on the cylinders 20 at the level of said openings are annular bosses 63 in which are provided at the inner sides of the cylinders annular channels 64 communicating with said openings. Fixed within the pistons 58 are hemi-spherical bearing plates 65 having annular flanges 66 fitting snugly within the skirts 59 of the pistons to seat flat against the lugs 61 and mating with said plates are like truncated bearing plates 67 having annular flanges 68 confronting the flanges 66. Interposed between said flanges are shims 69 and extending through both flanges are bolts 70 screwed into the pistons medially of the slots 60. Extending between the pistons and the crank shaft 11 are connecting rods 71 each of which preferably comprises, as shown in Fig. 1, a long lower section and a short upper section having detachable threaded connection with the lower section. The upper sections of said rods are formed with cupped bearing heads 72 slidably fitting between the coating bearing plates 65 and 67 of the pistons while the lower sections of said rods are provided with bearings 73 to cooperate with the crank shaft. Retained by the bearings 73 are roller bearings 74 surrounding the crank pins of the crank shaft, the bearings 74 being identical with the bearings 12. As will be seen, the heads 72 of the connecting rods will, as the pistons reciprocate, shift between the bearing plates 65 and 67, while wear upon these parts may be taken up from time to time by removing one or more of the shims 69 and tightening the bolts 70. Formed in the bearing plates 65 are axial passages 75 and formed through the connecting rods are passages 76 adapted to register at their upper ends with the passages 75. Suitably mounted adjacent to or on the crank case 10 is, as shown in Fig. 2, an appropriate oil pump 77 which, in this instance, is shown as driven by the crank shaft 11 through gears 78. Extending from the bottom of the crank case 10 to the pump is an inlet pipe 79 and leading from the pump to the gear case 26 is an outlet pipe 80. Leading from the gear case through the bearings 30 to open through the bushings 31 are passages 81. The bearings are further provided with passages 82 opening through the valve seats 29 and leading from the forward end of the gear case into the uppermost of the tubes 44 is a passage 83. Extending from the pipe 79 is a pipe 84 and connecting the latter pipe with the channels 64 of the cylinders 20 are branch pipes 85. In use, lubricant is, by removing the plug 28, introduced into the gear case 26 when the lubricant will flow through the passage 83 and through the tubes 44 into the crank case. Accordingly, when the engine is in operation, the lubricant will be drawn from the crank case by the pump 77 and delivered into the gear case 26 to gravitate downwardly through the passages 81 and 82 for lubricating the valves 33 and valve stems 34 while excess oil will return to the crank case through the passage 83 and tubes 44. 70 Also, some of the oil traveling in the pipe 80 will enter the pipe 84 and flow through the branches 85 into the channels 64 of the cylinders 20. From said channels, the oil will, of course, discharge through the openings 62 of the sleeves 55 into the cylinders. Thus, when the pistons move upwardly, the oil entering the cylinders will return through the lower ends of said cylinders to the crank case while, when the portions each 80 reach the bottom of their stroke and the slots 60 of the pistons are brought into register with the openings 62, as previously described, the oil will enter through said slots into the cups formed by the bearing plates 85 65 of the pistons. The openings 62 are arranged at spaced points clear around the sleeves 55 in order that should the pistons be caused to rotate for any reason, the slots 60 will always register with several of said 90 openings when the pistons each reach the lower end of their stroke. From the cups of the bearing plates 65 the oil will then gravitate downwardly through the passages 75 of said plates for lubricating the joints 95 between the bearing plates 65 and 67 and the heads 72 of the connecting rods, while the oil will also flow downwardly through the passages 76 of said connecting rods for lubricating the roller bearings 74 at the 100 crank pins of the crank shaft.

Having thus described the invention, I claim:

1. In an internal combustion engine, a crank case, a cylinder thereon, a head closing the cylinder, a valve within the head, a sleeve extending through the cylinder and carried thereby and projecting across the joint formed between the cylinder and head and engaging the valve and forming supporting means therefor, and means securing the head to the cylinder and both the head and cylinder to the crank case. 105
2. In an internal combustion engine, a crank case, a cylinder thereon, a head closing the cylinder, a valve within the head, a sleeve extending through the cylinder and across the joint formed between the cylinder and the head and engaging the valve to form supporting means therefor, and having an outer flange at its lower end underlapping the lower end of the cylinder and secured thereto, and means clamping the head to the cylinder and the cylinder to the crank case. 115
3. In an internal combustion engine, a crank case, a cylinder thereon, a head closing the cylinder, a valve within the head, means for supporting and regulating the seating of the valve, a sleeve carried by the cylinder and extending therethrough and 120
- 65 125
- the crank case by the pump 77 and delivered 130

across the joint formed between the cylinder and head and engaging the said valve to form supporting means therefor, and means for clamping the head to the cylinder and the cylinder to the crank case.

4. In an internal combustion engine, a crank case having an opening therein, a cylinder resting upon the crank case at said opening, a head closing the cylinder, a sleeve fitting in the cylinder and provided at its lower end with a flange fitting in said opening and centering the cylinder with respect thereto, means extending through said flange removably connecting the sleeve with said cylinder, and bolts engaging the head and crank case and clamping the cylinder therebetween.

5. In an internal combustion engine, a crank case having an opening therein, a cylinder resting upon the crank case at said opening, a separate head closing the cylinder, and a sleeve fitting in the cylinder and

provided at its lower end with a flange fitting in said opening and centering the cylinder with respect thereto, the sleeve extending through the cylinder into the head across the joint between the head and cylinder.

6. In an internal combustion engine, a crank case having an opening therein, a cylinder resting upon the crank case at said opening, a head closing the cylinder and provided with a valve seat, a valve rotatable in said seat to control the intake and exhaust of the cylinder, and a sleeve fitting in the cylinder and at its upper end touching the valve mating therewith, the sleeve and said valve covering the entire inner surface of the valve seat and cylinder and said sleeve being formed at its lower end with a flange fitting in said opening and centering the cylinder with respect thereto.

In testimony whereof I affix my signature.
EARL B. ALDOUS.
